UNITED STATES PATENT OFFICE.

CHARLES SNOW, OF MERIDEN, CONNECTICUT, ASSIGNOR TO THE MERIDEN CUTLERY COMPANY, OF SAME PLACE.

DESIGN FOR A TABLE-KNIFE.

SPECIFICATION forming part of Design No. 25,320, dated March 31, 1896.

Application filed February 29, 1896. Serial No. 581,398. Term of patent 3½ years.

to all whom it may concern:

Be it known that I, CHARLES SNOW, a citizen of the United States, residing at Meriden, the county of New Haven and State of Connecticut, have invented and produced a new and original Design for Table-Knives, which the following is a specification, reference being had therein to the accompanying drawings.

In the accompanying drawings, Figure 1 a side view, and Fig. 2 a back edge view, illustrating my design.

The leading feature of my design consists in the flat curved handle and the flat bolster which is flush with the inner part of the handle.

A denotes the blade, and B the handle integral therewith, said handle being curved and recurved at b and b', as more clearly shown in Fig. 2, which is a back edge view 20 of the knife and handle. The bolster portion C is flat and flush with the inner part of the handle, as more clearly shown in Fig. 2.

I claim—

The design for a table-knife substantially 25 as shown and described.

In testimony whereof I affix my signature in presence of two witnesses.

CHARLES SNOW.
